UNITED STATES PATENT OFFICE.

HENRY C. MILLER, OF WATERFORD, NEW YORK.

COLLAR.

941,795.

Specification of Letters Patent. Patented Nov. 30, 1909.

Application filed November 19, 1907. Serial No. 402,853.

To all whom it may concern:

Be it known that I, HENRY C. MILLER, a citizen of the United States, residing at Waterford, in the county of Saratoga and State of New York, have invented certain new and useful Improvements in Collars, of which the following is a specification.

My invention relates to improvements in fold collars and cuffs.

10 The main object is to construct a collar that when laundered and folded down it will not crack at the ends. Some of the primary causes of cracking of collars in the folding, after being starched are as follows:—The collar tops as heretofore made are thicker at their ends than at any other part of folding, caused by the inturning of the fold at the edges, thereby making it twice the amount of fabric at the ends than at 20 any part of the fold lines; and when seam dampened the thick part will not soften as readily as the thinner, therefore, the ends are more likely to crack. To prevent this, it is customary to give the ends an extra dampening, but as this is done by hand, and therefore not being always the proper amount the damage is not entirely eliminated. I have found furthermore, that where the two thicknesses are joined, 25 it has shown that it is the weakest part and when folded it will start to break at that point in the majority of cases, even when dampened by a seam dampening machine and then end dampened. But I have found that by eliminating the infolds entirely, 30 where they are in the line of fold I am able to fold from one to four ply thicknesses when starched, without damage and with less dampening. This is a great advantage 35 in laundrying, for it is well known that the collars are ironed in a flat state, and it is the desire of all laundrymen to keep as much of the finish that the ironing machine gives them as possible, and therefore 40 if a collar is seam dampened too much (which is preferably done on the wrong side of the collar) it will penetrate through and cause a rough finish, it will then have to be touched up by another operator. The 45 cutting away of the infolds also allows the collar to turn down more smoothly. The overseaming stitches that bind the raw edges are laid on lengthwise in direction of line of fold, so that the strain of fold- 50 ing will not come on them and cause them to break. These stitches giving a finished ap-

pearance to the raw edge. The ends may be made even lighter than the body of the collar by cutting out some of the lining completely and only over seam the facing plies. 60

Other objects and advantages will be hereinafter referred to and particularly pointed out in the claims.

Figure 1, showing a fold collar ironed flat. Fig. 2 showing the collar folded. Fig. 3 is a full sized collar end showing the over seam stitches. Fig. 4 shows the collar top before the rough edges to be over seamed are trimmed off. Fig. 5 shows a single ply of a collar before folding which also shows 70 the cutaway portion. Fig. 6 showing the infolds enlarged in cross section through X, Fig. 1. Fig. 7 shows a wing collar end which is over seamed at the line of fold.

In the drawings, 1, represents a collar 75 top; 2, the band of collar; 3, the inturn of folds; 4, the over seaming stitches; 5, the inturn of folds of the band; 6, the inserted lower edge of collar top; 8, the finishing stitches on band; 9, the finishing stitches on 80 top; 10, stitches holding the plies together at the cut out portion before trimming off the ragged edges which are overseamed by overseam stitches after trimming is done; 11, showing line of trimming the ragged 85 edge before overseam stitching; 12, ragged edge to be trimmed off before overseaming; 13, the infold cutaway part; 14, the collar top running stitch; 15, the line of shape after collar top is finished; 16, buttonhole; 18, 90 line of fold of wing collar.

To make the method of manufacture more clear so that those skilled in the art may be able to use my improvement, it is best to give a short and clear description of the collar top. 95

There are two ways to manufacture, one termed "hand-turning" and the other "machine-turning." I do not depart in either instance from the general way of making a 100 collar only, that the infold is cutaway in the facings as well as the lining. First we will take the hand turned collar. First the plies are cut, the ends having the appearance of solid lines Fig. 5, which show the 105 cutaway part 13, the three or more plies constituting the top are pasted together, then the running stitches 14, are stitched, then the collar top is turned inside out so that it will assume the shape of dotted lines 110 15, and the solid lines, Fig. 4. The raw edges 12 of cut away part 13, are then pulled

out and smoothed when the finishing stitches 9, are then stitched, then the raw edge holding stitches 10, are stitched, this holds the raw edges tight and all the plies even so 5 that when the raw edges are trimmed off on line 11, it is in perfect alinement with end edge of collar top; when this is done the overseaming stitches 4, are as in Figs. 1, 10 2, 3; as will be noticed that the overseam laps over a part of the infolds, this is to insure 15 against the raveling of the raw edges; after the over stitching is completed in both ends of the collar top, the lower edge 6, is trimmed and banded; and as the banding is no part of this invention so it will be superfluous to mention it.

In the machine turned collar, the collar top plies are cut out exactly as the hand turned collar plies; the plies are put in a 20 turning machine which are equipped with folding devices of a shape for the style to be turned, which turns the folds 3, inwardly on the two ends and top simultaneously at line 15, Fig. 5; when the two sides are turned 25 they are placed together with the inturned folds on the inside and are stitched with finishing stitches 9, being only one line of stitching against the two of the hand turning. The lap being so narrow that the cut 30 away part 13, Fig. 5, that the turning machine will not affect this part, but will leave it extend outwardly ready to be trimmed, stitched, and overseamed and then banded as in the hand turned collar; this method 35 may also be adapted to advantage on a wing collar as in Fig. 7, which will prevent the same cracking when folded at line 18.

What I claim is:

1. A collar comprising a plurality of plies connected to provide infolding edges, and 40 adapted to be folded along a longitudinal line and the edges being cut away in part upon one side of the longitudinal line of fold, and means for reinforcing the collar edge adjacent the cut away portions. 45

2. A collar comprising a plurality of plies of textile fabric connected to provide infolding edges and adapted to be folded along a longitudinal line, and said infolding edges being cut away in part upon one side 50 of the longitudinal line of fold, and stitches reinforcing the collar edge adjacent the cut away portions.

3. A collar comprising a plurality of plies infolded on the edges and sewed together, 55 all of the infolds being cut away on the longitudinal line of fold, and over stitches close together and touching each other passing around the cut away edges to prevent the same raveling, said stitches being in direction of the folds on the edge of the collar 60 above the longitudinal line of fold.

4. A collar comprising a plurality of plies connected to provide infolding edges and having a line of fold, the folded edges being 65 cut away in part upon one side of the line of fold, and means for reinforcing the collar edge adjacent the cut away portions.

In testimony whereof I affix my signature in presence of two witnesses.

HENRY C. MILLER.
